DESIGN FOR A HEATER CASING

Carl E. Meyerhoefer, Brooklyn, N. Y., assignor to
E. A. Laboratories, Inc., Brooklyn, N. Y., a
corporation of New York

Application March 18, 1938, Serial No. 75,915

Term of patent 3½ years

To all whom it may concern:

Be it known that I, Carl E. Meyerhoefer, a citizen of Germany, residing at Brooklyn, in the county of Kings and State of New York, have invented a new, original, and ornamental Design for Heater Casing, of which the following is a specification, reference being had to the accompanying drawing, forming a part thereof, wherein:

Fig. 1 is a perspective view of my new design for heater casing, and

Fig. 2 is a plan view thereof.

The characteristic features of my design reside in the combination with the casing disclosed of the diagonal arrangement of the handles on the deflectors as shown.

I claim:

The ornamental design for a heater casing, as shown and described.

CARL E. MEYERHOEFER.
